UNITED STATES PATENT OFFICE.

RICHARD T. BISHOP, OF ST. LOUIS, MISSOURI, ASSIGNOR OF ONE-HALF TO
THEODORE HUNT, OF SAME PLACE.

FENDER FOR RAILWAY-CARS.

SPECIFICATION forming part of Letters Patent No. 276,999, dated May 8, 1883.

Application filed March 22, 1883. (No model.)

To all whom it may concern:

Be it known that I, RICHARD T. BISHOP, a citizen of the United States, residing at St. Louis, in the county of St. Louis and State of Missouri, have invented a new and useful Fender for Street and other Railroad Cars, of which the following is a specification, reference being had to the accompanying drawings.

This invention relates to fenders for street and other railroad cars; and it consists in certain improvements in the construction of the same, which will be hereinafter fully described, and particularly pointed out in the claims.

In the drawings hereto annexed, Figure 1 is a side view of a car-truck equipped with my improved fenders. Fig. 2 is a transverse vertical sectional view of the same. Fig. 3 is a horizontal section, and Fig. 4 is a view of one of the fenders detached from the truck.

20 The same letters refer to the same parts in all the figures.

25 A in the drawings designates the truck, B the axle-boxes, C the axles, and D the wheels, all of which are constructed and arranged in the usual well-known or in any suitable manner, with the exception that the axle-boxes may be provided with collars E upon their inner sides surrounding the bearings of the axles, and with shoulders F above the same, inside of 30 and adjoining the hangers G, in which the axle-boxes are mounted, the object of which will be presently described.

35 H H are the fenders, which are provided at their ends with suitably-curved shields or wheel-guards, I, which are extended and curved around the wheels at the ends of the car, substantially as shown. The fenders H are provided with upwardly-projecting brackets J J, having vertical slots K K, which are fitted upon the collars E upon the inner sides of the axle-boxes, upon which the fenders may thus slide vertically.

40 L L are longitudinal rods, having wings M resting upon the shoulders F of the axle-boxes, and sliding longitudinally upon the same. The wings M M have diagonal or inclined slots N N, to receive studs O O, projecting laterally from the upper ends of the brackets J of the fenders, which said studs may, if 45 desired, be provided with friction-rollers P, in order to render the operation more easy. It

will be seen from this construction that by moving the rods L longitudinally the fenders may be raised or lowered, as desired. Normally, they are intended to be lowered, so as to serve as guards for the wheels, remove small obstructions from in front of the same, and prevent serious accidents to persons who may fall or stumble in front of the car. Should any obstructions be encountered that might prove 60 destructive to the fenders, the latter may be raised so as to pass over such obstructions.

For the purpose of manipulating the fenders I may avail myself of mechanism such as illustrated in the drawings, which is as follows: 65

Q Q are hangers or brackets at the ends of the truck, to which are pivoted levers R R, the upper ends of which may engage segmental racks S, for holding them in any position to which they may be adjusted. The said levers 70 are provided with slots T above their fulcrums to receive rods or bars U, which connect the ends of the operating rods L, which may thus be simultaneously operated by operating either of the levers. The latter should not engage 75 the ratchet-bars, except for the purpose of holding the fenders in a raised position, when this shall be deemed desirable.

1 prefer to make the collars E upon the inner sides of the axle-boxes dovetailed, and the upper ends of the slots K in the brackets J of the fenders correspondingly dovetailed, as shown, respectively, at V and W, for the purpose of holding the parts well together. 80

85 My improved fenders, it will be seen, are simple and convenient, and may readily be applied to any car-truck now in use.

I claim as my invention and desire to secure by Letters Patent of the United States—

1. The combination, with the axle-boxes having dovetailed flanges or collars surrounding the bearings of the axles, of the fenders having brackets provided with vertical dovetailed slots, as set forth. 90

2. The combination, with the vertically-sliding fenders having laterally-projecting studs or friction-rollers, of the longitudinally-sliding rods having diagonally-slotted wings or plates, substantially as and for the purpose set forth. 95

3. The combination of the car-truck, the axle-boxes having inwardly-projecting collars surrounding the axle-bearings, and laterally-pro-

jecting shoulders above the same, the fenders having vertically-slotted brackets adjustable upon the said collars, and provided with laterally-projecting studs or friction-rollers, and the 5 longitudinal operating-rod, having diagonally-slotted plates, by which they slide upon the shoulders of the axle-boxes, all arranged and operating substantially as set forth.

4. The combination, with the vertically-sliding fenders and the longitudinally-sliding operating-rod, arranged substantially as described, 10 of levers mounted in suitable hangers at the

ends of the truck, and transverse rods connecting the ends of the operating-rod and working in slots in the said levers, substantially as 15 set forth.

In testimony that I claim the foregoing as my own I have hereto affixed my signature in presence of two witnesses.

RICHARD THOMAS BISHOP.
